(57) **CLAIM**

The ornamental design for a connector, as shown and described.

DESCRIPTION

FIG. 1 is a front perspective view of a connector showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is an enlarged view of one of the contact members as shown in FIG. 1 with environment removed for clarity purposes.

The broken lines immediately adjacent to the shaded areas represents the bounds of the claimed design and form no part thereof. The broken lines depicting the remainder of the connector show features that form no part of the claimed design.
